(57) CLAIM

The ornamental design for a headlight for a motorcycle, as shown and described.

DESCRIPTION

FIG. 1 is a first perspective view of a headlight for a motorcycle showing our new design;

FIG. 2 is a front elevation view thereof;

FIG. 3 is a top plan view thereof;

FIG. 4 is a bottom plan view thereof; and,

FIG. 5 is a right side elevation view thereof, the left side elevation view being a mirror image thereof.

The broken lines in the drawings illustrate portions of the headlight for a motorcycle which form no part of the claimed design.
